JOHN LUNDIE, OF NEW YORK, N. Y., AND WILLIAM R. DUNHAM, JR., OF NEW HAVEN, CONNECTICUT.

RAILWAY-RAIL.

1,380,725.

Specification of Letters Patent. Patented June 7, 1921.

Application filed November 16, 1920. Serial No. 424,391.

To all whom it may concern:

Be it known that we, JOHN LUNDIE and WILLIAM R. DUNHAM, Jr., both citizens of the United States, residing, respectively, at 5 New York, New York, and New Haven, Connecticut, have invented certain new and useful Improvements in Railway-Rails, of which the following is a specification.

This invention relates to railway rails either for electric or steam railroads. One of the objects of the invention is to provide means for seating railway rails upon the wooden ties, the under surface of the rail base being provided with means for seating 10 upon and embedding in the ties. In the case of rails under light wheel loads, tie-plates are not ordinarily employed, so that under the present invention the rail rests directly upon and engages the wood fibers 15 of the ties. Another object of the invention is to provide an inclined rail with a base so constructed that the line of stress due to the load on the usual beveled wheel-tread passes axially through the web, and is at 20 right angles to the series of inclined seats on the bottom of the base, the rail being thus held firmly to gage without in any way cutting or injuring the surface of the ties.

These being among the objects of the present invention the same consists of certain features of construction and combinations of parts to be hereinafter described, and then claimed with reference to the accompanying drawings showing two embodiments of the invention, in which—

Figure 1 is a transverse section of an inclined street railway rail, according to the present invention, showing the same seated 40 upon the tie, and also showing a portion of a car wheel;

Fig. 2 is a similar view of a rail for steam roads, according to the present invention; and

Fig. 3 is an underside view of the rail showing the ends only, the intermediate portion being broken away.

Although the invention is here shown as applied to inclined rails, some of the features of the invention may be capable of use in a vertical rail.

Referring to Figs. 1 and 2, the rail has a base 10, and a web 11, the web being in-

clined away from a vertical plane. The rail shown in Fig. 1 is for street railways, and 55 it is provided with a head 12, as customarily shaped for that purpose. The rail shown in Fig. 2 is for steam roads, and has the customary head 12^a.

When the present invention is applied to 60 inclined rails, the entire structure is inclined relatively to the horizontal plane of the general undersurface of the rail base, that is to say, its transverse axis is inclined substantially as indicated by the dotted line *a*, 65 Fig. 1. The vertical is indicated by the dotted line *b*.

The preferred construction of the undersurface of the base 10 of the rail is as follows: The undersurface is formed by a series of inclined seats 13, preferably connected by curved portions 14. In the preferred construction, the seats 13 and the connecting portions 14 between the seats, extend longitudinally of the rail, preferably 70 parallel with the longitudinal axis of the rail. Said seats 13 also extend in inclined planes, preferably parallel with each other, said planes being perpendicular to the inclined axis *a* of the rail. Said seats 13, except for small seating portions which may be at the edges of the base of the rail, are 75 both of substantially the same width. In Fig. 1, the dotted line *c* indicates the direction of inclination of the seating or step surfaces 13 transversely of the rail, while the dotted line *d* is a line substantially parallel 80 with the longitudinal axis of any tie. The car wheel 15 is of the usual beveled or standard type, having a beveled tread 16. 90

It will be seen from the preferred form of the invention that the seating surfaces 13 are the major seating surfaces of the rail, and that they offer more resistance to the seating of the rail in the top of a wooden 95 tie than the connecting surfaces 14, which lie at a greater angle of inclination to the plane of the base, or top surface of the tie, and which may be said to constitute minor seating surfaces.

From the above description of the preferred form of the invention it will be seen that the line of pressure in the wheel and the line of stress in the rail are co-incident, being represented by the line *a*. It will also 105 be seen that the tread of the wheel and the

bearing surface therefor of the rail are substantially at right angles to the line *a*, at any point along the rail over which the wheel is passing. It will also be seen that if the left-hand end of any tie be considered the outside of the track, the shoulders or surfaces at 14 will be at those sides of the successive seating surfaces 13, excepting the last one to the right, which are away from that end of the tie. It will also be seen by the arrow indications in Fig. 1 that the resisting forces of a tie are at right angles to the direction of seating, thus preventing slipping. The action may be described in the following terms, so far as the preferred embodiment of the invention is concerned: The line of stress *a*, due to the load on the usual beveled wheel tread 16 passes axially through the web, and is at right angles to the series of inclined seats 13 on the bottom of the base, such seats being parallel with the bevel of the wheel tread, so that the rail is held firmly to gage. It will be seen that the described undersurface of the base will not in any way cut or injure the surface of the tie, as it merely becomes slightly embedded therein, due to the preferred shallow or slight depth of the ribs, the fibers of the tie accommodating themselves to the contour of the said under surface.

In one aspect the under surface of the base of the rail may be considered as developed in waves, the crests of which at 14 and the intermediate troughs of which extend in lines substantially parallel with the longitudinal axis of the rail; and preferably, the so-formed ribs are defined by planes, joined by curves at the juncture of neighboring ribs and at the edge of each rib, which follow substantially the lines of obtuse angles.

The curves referred to are reverse curves, that is to say, the curve at the edge of each rib is convex, and the curve at the juncture of the ribs with each other is a concaved curve.

Railway engineers will appreciate many of the advantages of the present invention, and it is believed unnecessary to specify just what objections to vertical rails of the type referred to are overcome, when the invention is applied to inclined rails.

It is obvious that the invention is susceptible of more or less modification,—as, for instance, it may be applied to vertical rails,—and that such modifications would still be within the appended claims.

What I claim as new is:

1. A railway rail, the base of which has a plurality of longitudinal tie-engaging elements, corresponding, opposite, surfaces of which are disposed at different inclinations to the plane of the base.

2. A railway rail, having its head and web inclined to its base, the base having tie-en-

gaging and seating elements with contact surfaces at right angles to the plane of inclination.

3. A railway rail, having a series of inclined seats on the bottom of its base, and which are parallel to the bevel of the wheel-tread, in which rail the line of stress, due to the load on the wheel, passes axially through the web and is at right-angles to the inclined seats. 75

4. A railway rail, having a series of inclined seats on the bottom of its base, and which are parallel to the bevel of the wheel-tread, in which rail the line of stress, due to the load on the wheel, passes axially through the web and is at right-angles to the inclined seats, said seats extending throughout the length of the rail. 80

5. A railway rail, having a series of inclined seats on the bottom of its base, and which are parallel to the bevel of the wheel-tread, in which rail the line of stress, due to the load on the wheel, passes axially through the web and is at right-angles to the inclined seats, said seats extending throughout the length of the rail, and the series covering substantially the width of the rail-base. 85 90

6. A railway rail, having a series of inclined seats on the bottom of its base, and which are parallel to the bevel of the wheel-tread, in which rail the line of stress, due to the load on the wheel, passes axially through the web and is at right-angles to the inclined seats, said seats defining the bottom of the base in longitudinal, parallel, planes, and being joined by connecting surfaces. 95 100

7. An inclined railway rail, the under surface of the base of which is developed in waves, the crests and troughs of which are formed by reverse curves and extend in lines substantially parallel with the longitudinal axis of the rail, and enter and seat on the surface of a wooden tie to hold the rail to gage. 105 110

8. An inclined railway rail, the under surface of the base of which is developed in waves, the waved portions extending in lines substantially parallel with the longitudinal axis of the rail and are formed by planes joined by curves, which follow substantially the lines of obtuse angles, to enter and seat on the surface of a tie to hold the rail to gage. 115 120

9. An inclined railway rail, the base of which has a plurality of under, parallel, ribs; with surfaces at right angles to the plane of inclination.

10. An inclined railway rail, the base of which has a plurality of longitudinal tie-engaging elements, corresponding, opposite, surfaces of which are disposed at different inclinations to the plane of the base. 125

11. A railway rail, the base of which has 130

a plurality of longitudinal tie-engaging elements, corresponding, opposite, surfaces of which are disposed in different planes, the said planes of each element meeting at an obtuse angle.

12. A railway rail having a series of spaced, longitudinal, seats on the bottom of its base, which are parallel with each other, and in which rail the web is substantially at right angles to the said seats.

13. A railway rail having a series of spaced, longitudinal, seats on the bottom of its base, which are parallel with each other, and in which rail the web is substantially at right angles to the said seats, said seats extending throughout the length of the rail.

14. A railway rail having a series of spaced, longitudinal, seats on the bottom of its base, which are parallel with each other, said seats being also joined by connecting surfaces disposed at an angle thereto, and in which rail the web is substantially at right angles to the said seats.

15. A railway rail having a series of spaced, longitudinal, seats on the bottom of its base, which are parallel with each other and in which rail the web is substantially at right angles to the said seats, and the series covering substantially the width of the rail-base.

16. An inclined railway rail, the base of which has a plurality of longitudinal tie-engaging elements, corresponding, opposite, surfaces of which are disposed at different inclinations to the plane of the base, the less inclined of said surfaces constituting the major bearing surfaces of the base and extending in planes substantially at right angles to the inclination of the rail.

17. An inclined railway rail, the base of which has a series of spaced, longitudinal, seats on its undersurface, which are substantially parallel with each other, the

planes of said seats being substantially at right angles to the web of the rail, and substantially parallel with the bearing surface of the rail-head.

18. An inclined railway rail, the base of which has a series of spaced, longitudinal, seats on its undersurface, which are substantially parallel with each other, the planes of said seats being substantially at right angles to the web of the rail and substantially parallel with the bearing surface of the rail-head, said seats extending throughout the length of the rail.

19. An inclined railway rail, in which its base is provided with stepped seating surfaces.

20. A railway rail, in which its base is provided with major seating surfaces to take up the load on the tie, and minor seating surfaces connecting the major seating surfaces and offering less resistance to the seating of the rail than said major seating surfaces.

21. An inclined railway rail, in which the head and web are inclined to the base, the base being provided with major seating surfaces, which lie in planes substantially at right angles to the upward plane of the head and web, to take up the load on the tie, and minor seating surfaces connecting the major seating surfaces and offering less resistance to the seating of the rail than said major seating surfaces.
